UNITED STATES PATENT OFFICE.

OSCAR L. MILES, OF VAN BUREN, ARKANSAS.

STRIP HOLDING AND EXHIBITING BOX.

SPECIFICATION forming part of Letters Patent No. 633,604, dated September 26, 1899.

Application filed December 14, 1898. Serial No. 699,276. (No model.)

To all whom it may concern:

Be it known that I, OSCAR L. MILES, a citizen of the United States, residing at Van Buren, in the county of Crawford and State 5 of Arkansas, have invented certain new and useful Improvements in Strip Holding and Exhibiting Boxes; and I do hereby declare the following to be a full, clear, and exact description of the invention, which will enable others skilled in the art to which it appertains to make and use the same.

My invention relates to improvements in strip holding and exhibiting boxes, but relates more particularly to boxes adapted to 15 be used in connection with the improved form of auditor's train-sheet described in an application for patent, Serial No. 699,275, filed on even date herewith, and in connection with the art and means for checking and auditing the earnings of passenger-trains, application, Serial No. 699,274, filed on even date herewith. My invention, however, may be used for any purpose wherein contained 20 and a portion thereof is exhibited a long sheet of flexible material, such as paper—as, for instance, in calendars, advertising devices, and such like.

In order to better comprehend the nature of my said invention, attention is called to 30 the accompanying drawings, forming a part of the specification, and in which—

Figure 1 is a front elevation of the box; Fig. 2, a side elevation thereof. Fig. 3 is a section taken on the line 3 3 of Fig. 2. Fig. 35 4 is a section taken on the line 4 4 of Fig. 1. Fig. 5 is a face view of the roll-supporting spring, and Fig. 6 is a sectional view of a modification of one of the rolls.

In all the above views corresponding parts 40 are designated by like numerals of reference.

The register is rectangular in shape and is formed with a base or back 1, sides 2 2, and ends 3 3, made of wood or metal and secured together in any suitable way, as by screws 45 or glue. The particular construction of the box does not affect the spirit of the invention.

Across the face of the box are two cleats or cross-bars 4 4, fastened in place, as with wood-screws, as shown. Hinged to the cleats 50 are the doors or flaps 5 5, which abut against the sides 2 2 and ends 3 3 of the box and may be sealed or locked thereto. The abutting

edges of the cross-bars 4 are preferably beveled at 6, as shown in Fig. 2. Between the cross-bars 4 4 and slightly below the level of the bottom of the same is arranged the flat table 7. This table is so arranged that its outer face is upon the same plane as the under faces of the cross-bars. The edges 8 of the table, adjacent to the beveled portions 6 60 of the cross-bars 4, may be beveled or rounded, as shown.

Within the boxes are arranged the rolls 9 10. The said rolls are cylindrical in shape and are preferably provided with flanges 11 65 at or adjacent to the extremities thereof to guide the material carried thereon. The roll 10 is provided with pins 12 13, which serve as supporting-axes for the same. The pin 12 is supported within the socket 14, formed 70 in one of the sides 2 of the box. The opposite pin 13 is introduced within a bearing 15, formed within the spring 16, as shown in Fig. 5. This spring is formed with a curved portion 17, as shown, and is attached to the sides 75 of the box by means of suitable screws 18 19. The screw 19 passes through a slot 20, formed in the spring, which will allow the latter to slightly flatten against the elasticity of the metal. The roller is easily introduced within 80 its bearings by first placing the pin 12 within the opening 14 and then introducing the other pin within its bearing, the spring 16 bending sufficiently to allow of this being done. The spring will serve to retain the roll in position, 85 and by bearing against one extremity with considerable pressure will prevent it from becoming accidentally rotated. The roll 9 is supported in the same manner at one end; but the other extremity is provided with a 90

larger pin 21, which is squared or otherwise molded for the attachment of a key or crank 22, by means of which the roll may be rotated. Adjacent to one extremity of the roll 9 is a ratchet-wheel 23. This wheel may also 95 serve in lieu of one of the flanges 11. A spring - actuated pawl 24 is attached to a bracket 25, screwed or otherwise secured to one of the sides 2 of the box. This pawl engaging with the ratchet-teeth will effectively 100 prevent the roll from being rotated in a reverse direction unless the box first be opened and the pawl disengaged. A lock or seal 26 is provided to allow the compartment contain-

ing the roll 9 to be closed, and an additional lock 27 may serve the same purpose as to the compartment occupied by the roll 10. The space between the cross-bars 4 over the 5 table may be covered by a transparent window 28, hinged to one of the cross-bars 4 and provided with a snap or catch upon the other cross-bar.

In the modification shown in Fig. 6 the 10 rolls are shown as made in the form of hollow tubes 29 of metal or paper, in the extremities of which are inserted the tapered wooden plugs 30, the latter having formed integrally thereon either the flanges 31 or the 15 ratchet 32, as the case may be. Suitable bearing-pins 33 and 34 are provided to form journals upon which the rolls are supported. These pins may have enlarged heads, whereby they will be permanently held within 20 their bearings. In this modification the tubular roll may be removed from the box without disturbing the supporting end plugs and bearing.

In connection with the improved box I 25 contemplate using a long strip of flexible material, which is used as an auditor's train-slip by having printed thereon in large letters the names of stations by which the car is run and between said station - names blank spaces, 30 within which may be indicated from time to time numerals or other designations indicating the number of passengers within said car between the adjacent stations. It is necessary that the said box be conspicuously 35 hung within the car, and for that purpose are provided the supports 35 at the top of the box.

In operating, the strip is first wound upon

the roll 10, which is inserted within the box, a short portion being left for attachment to 40 the roll 9. Before attaching to the roll 9 the strip is passed over the table and through the openings formed by the bevels 6 and 8. The latter will render the insertion of the strip very much easier than if the cross-bars were 45 not beveled. In applying the key 22 to the bearing 21 of the roll 9 the strip may be wound upon the roll and gradually transferred from the roll 10, the entire strip passing over the table and under the sight. 50

Having now described my invention, what I claim as new therein, and desire to secure by Letters Patent, is—

1. In a strip holding and exhibiting device, the combination with the box having the 55 sides 2, 2, the table 7 secured to and connecting said sides, with its outside face on the same plane as the abutting edges of said sides, the cleats 4, 4, arranged parallel to said table, the flaps 5, 5, hinged to said cleats, and the 60 rolls 9, 10, arranged within said box, and means for rotating the same, substantially as described.

2. A strip-holding device, and a support therefor, consisting of a spring 16, provided 65 with a curved portion 17, having the opening 15 therein, the supporting-screw 18, the slot 20, and guide-screw 19, substantially as described.

This specification signed and witnessed this 70 9th day of December, 1898.

OSCAR L. MILES.
